UNITED STATES PATENT OFFICE

2,084,494

REFRIGERATING APPARATUS

Harry B. Hull, Dayton, Ohio, assignor, by mesne assignments, to General Motors Corporation, a corporation of Delaware

Application November 26, 1932, Serial No. 644,477

16 Claims. (Cl. 62—116)

This invention relates to refrigerating apparatus and more particularly to a refrigerator having a removable sealed compression refrigeration system provided with a continuous operating compressor.

At the present time, substantially all of the compression type of household refrigerating systems are built along two general designs. In one design, the compressor, condenser and the electric driving motor are placed in the machinery compartment beneath the food compartment. These elements are connected by refrigerant conduits which pierce the rear wall of the refrigerator cabinet and connect to an evaporator inside of the food compartment. In this design an open type of electric motor generally drives a piston type compressor through a belt and pulleys. The system is controlled by starting and stopping the electric motor at suitable times to provide the proper temperature within the food compartment.

Another general type of refrigerator is that in which the machinery compartment is provided above the food compartment. In this type, there is ordinarily provided what is called a sealed unit, which contains an electric motor and a compressor, as well as a condenser. These elements are mounted upon a removable partition which divides the machinery compartment from the food compartment and on the underside of this removable partition there is mounted an evaporator which is connected to the compressor and condenser above the partition. This type of system is also controlled by starting and stopping the electric motor. In this type the top cover of the machinery compartment is readily removable and the entire refrigerating system may be removed as a whole by removing the partition upon which it is mounted.

While a cabinet so constructed permits easy removal of the refrigerating system, it is in some ways more costly to construct and has the further disadvantage that it places the food compartment below the most convenient height. Inasmuch as the system operates intermittently, it is necessary that the condenser and compressor have a fairly large capacity, necessitating a more costly refrigerating unit.

It is therefore an object of my invention to provide a refrigerator of low cost having a removable sealed refrigerating system provided with a continuously operating compressor which is mounted beneath the food compartment so that the food compartment is maintained at a convenient height.

It is another object of my invention to so construct the refrigerating system that it may be easily shipped and easily installed or removed from the refrigerator cabinet without opening or breaking the seal on the refrigerating system.

It is another object of my invention to provide an improved control means for the continuous operating refrigerating system which will maintain the food compartment at a proper temperature and also provide additional refrigerating effect when it is desired to freeze ice cubes or similar articles within the evaporator.

Further objects and advantages of the present invention will be apparent from the following description, reference being had to the accompanying drawings, wherein a preferred form of the present invention is clearly shown.

In the drawings:

Fig. 1 is a side vertical sectional view of a refrigerator embodying my invention;

Fig. 2 is a sectional view showing a refrigerating system packed in a box for shipment;

Fig. 3 is a view showing the refrigerating system removed from the box;

Fig. 4 is a fragmentary top view of the refrigerating system shown in Fig. 3 showing a portion of one of the mounting brackets;

Fig. 5 is a perspective view showing a portion of the cabinet construction, particularly made so as to enable the refrigerating system to be readily installed and removed from the cabinet;

Fig. 6 is a fragmentary view, partly in section, of the upper front portion of the box. The part in section is taken along line 6—6 of Figure 7, and

Fig. 7 is a sectional view along the line 7—7 of Fig. 6.

Referring to the drawings and more particularly to Fig. 1, there is shown a refrigerator cabinet 20 having a food compartment 21 therein provided with insulated walls and a door opening 22 provided with an insulated refrigerator door 23.

In order to cool the food compartment 21, I provide an improved type of refrigerating system. This system has a flat plate type condenser 24 mounted on the rear wall of the refrigerator cabinet. The condenser 24 has a pair of sheets of metal welded together and provided with refrigerant passages therebetween. At the edge portions of the condenser 24 there is provided attaching flanges 25 which are first bent rearwardly and then forwardly and provided with a flanged edge 26, better shown in Fig. 4, which is fastened to the rear wall of the cabinet. The rearwardly projecting portion 25 during normal operation of the system is placed against a wall

so that it forms a sort of a chimney for air to pass upwardly upon the outer side of the condenser, while the rear wall of the cabinet and the condenser form another chimney to promote air circulation over the inner surface of the condenser so as to cool and liquefy the refrigerant in the condenser 24.

In order to supply liquid refrigerant to the evaporator, the bottom of the condenser is connected by means of a flexible conduit 29 to a thermostatic expansion valve 30 mounted upon the evaporator 31 which is fastened to the top of the food compartment 21 and located in the upper portion thereof. The evaporator 31 is of a peculiar sheet metal type which is generally U-shaped. It is provided with a header or distributing duct 32 which extends from front to rear at the top of the evaporator upon one side and a second header 33 which extends along the other side of the evaporator. The refrigerant, after passing through the expansion valve 30, is conducted through a conduit 34 to the header 32. The header 32 is connected by refrigerant passages which extend down one side of the evaporator 25 and up the other side to the header 33 upon the opposite side of the evaporator and the liquid refrigerant distributes itself into these refrigerant passages and is conducted through the passages toward the other header 33. The liquid refrigerant is vaporized in the refrigerant passages before it reaches the header 33 and therefore reaches the header 33 in vapor form and is conducted to the compressor through a flexible return conduit 35. This removes heat from the food compartment 21 and the ice tray shelves 36. The evaporator 31 is provided with ice tray shelves 36 which support the ice trays 37.

The ice tray shelves 36 have a rear portion 38 upon which is mounted a thermostatic bulb 39 which is connected by a tube 40 to the valve portion of the thermostatic valve 30. The bulb in this location is exposed to air within the food compartment 21 and is also subject to the influence of the ice trays by being thermally connected therewith through the ice tray shelves 36. In this way, under normal conditions, the thermostatic bulb 39 is almost wholly under the influence of the circulating air within the food compartment 21. However, when an ice tray is filled 50 with water and placed in the evaporator, the heat given off by the water in the ice tray will travel through the ice tray shelf to the thermostatic bulb 39 which will become heated and act upon the valve 30 so as to cause more refrigerant to be introduced into the evaporator so that the freezing water within the ice tray will be hastened.

The refrigerant which vaporizes in the evaporator, is collected in the small header 33 and is returned through a flexible return conduit 35 to a sealed motor-compressor unit 28 which is removably suspended from the bottom of the food compartment 21. The motor-compressor unit 28 contains a compressor and an electric motor which continuously drives the compressor, all of which is enclosed within a sealed housing. The compressor removes the vaporized refrigerant from the flexible return conduit 35 and forces the refrigerant into a flexible supply conduit 27 which conducts the compressed refrigerant to the top of the condenser 24.

In order to facilitate installation, repair and removal of the refrigerating system without disturbing any refrigerant connections thereof, I have devised a means and method by which the sealed motor compressor unit 28 and the evapo-

rator 31 may be removed from their positions and mounted by special mounting means on the rear side of the condenser 24, as shown in dotted lines at the rear of the cabinet in Fig. 1, after which the whole assembly may be removed and packed in a box as shown in Fig. 2. In order to do this, I have mounted the compressor 28 so that it may be easily removed from its position beneath the food compartment 21 and I have provided bolt holes in the flanges of the condenser so that mounting brackets such as the mounting brackets 41 and 42 may be fastened to the back of the condenser 24 by suitable bolts 43, 44. These mounting brackets are connected to the motor compressor unit 28 by studs 45 and 46 which are also used in supporting the sealed motor-compressor unit 28 when it is at its normal position beneath the food compartment 21. If desired, the compressor and the evaporator may be connected directly to the condenser without the intervention of mounting brackets. The refrigerant conduits are all of thin flexible tubing and may be bent in any desired direction without substantial injury.

By opening the refrigerator door 23 and by removing the top ornamental cover 56 from the cabinet as well as by removing the ornamental nameplate 59 at the front of the cabinet, the evaporator 31 may also be removed from the cabinet and fastened to similar mounting brackets 48 and 49 which may then be connected to the condenser in a manner similar to that of the compressor by suitable bolts 50 and 51. The compressor and evaporator are both of comparatively light weight so that one man can remove each of these units from the cabinet without assistance. After the evaporator and compressor are removed from the cabinet, the condenser may then be removed from the rear wall of the cabinet and can be placed in a suitable packing box 40 52 shown in Fig. 2 for shipment. The refrigerating system removed from the cabinet is shown in Fig. 3.

In order to provide for the refrigerant conduits 29 and 35 extending to and from the evaporator 21, there is a vertical depression (see Figs. 5, 6 and 7) in the outer sheet metal wall 54 of the cabinet 20 which provides a vertical notch 55 extending upwardly from the door opening 22. The door opening 22 is surrounded by a door moulding 56 of a suitable material having low heat conductivity such as wood and this moulding is provided with a notch 57 which connects with the vertical notch 55. A rubber covering 58 is provided for that portion of the flexible 55 refrigerant conduits 29 and 35 which extends through the notches 55 and 57. This covering is made of such a shape so as to properly fit and fill each of these notches.

In order to conceal the presence of these notches, the lower angle portion of the rubber outer covering for the refrigerant conduits is made of such a shape that it presents a surface continuous with the exposed surface of the door moulding 56. Likewise, the vertical portion of this rubber covering is also provided with a surface so as to make it practically continuous with the outer surface of the refrigerator cabinet 20. In addition, however, an ornamental nameplate 59 is provided with ornamental upper and lower 70 extensions 60 and 61 which fit over the vertical notch 55 and cover the rubber covering 58 of the refrigerant conduits 35 and 29. The ornamental nameplate 59 is fastened to the front of cabinet by a pair of screws 64. In order to cover the por- 75

tion of the refrigerant conduits 29 and 35 which extends over the top wall of the food compartment and to cover the projecting upper ends of the outer sheet metal walls, I provide an ornamental top sheet metal cover 66 provided with a flange 67 which extends over the outer vertical sheet metal walls and which extends over and overlaps the upper portion of the ornamental nameplate 59. The flange portion of the door 23 also overlaps the lower portion of ornamental nameplate 59.

In this way the refrigerant conduits are concealed so that the general public will not be aware of the fact that the surface of the refrigerator 15 has been notched to provide a place for the connecting refrigerant conduits. By this type of construction the advantages of both types of refrigerating systems are retained and the disadvantages thereof are avoided. By merely removing the ornamental nameplate and the ornamental top cover of the cabinet, the entire refrigerating system may be removed without being disrupted.

While the form of embodiment of the invention 25 as herein disclosed constitutes a preferred form, it is to be understood that other forms might be adopted, all coming within the scope of the claims which follow.

What is claimed is as follows:

1. Refrigerating apparatus including a cabinet having an insulated food compartment therein, a refrigerating system for cooling the food compartment including an evaporating means within the food compartment and a refrigerant liquefying means located outside the food compartment, said liquefying means including a refrigerant compressor located beneath the food compartment, said food compartment having a door opening and a door therefor, refrigerant conduit means 30 extending from the evaporating means to the door opening and from the door opening up over the front wall of the cabinet, rearwardly over the top of the food compartment and down the back of the food compartment to the compressor, and ornamental covering means extending over the 35 exposed portions of the refrigerant conduit means for concealing the conduit means.

2. Refrigerating apparatus including an insulated cabinet containing a food compartment 50 therein having a door opening and a door therefor, a condenser fastened to the rear wall of the food compartment, a refrigerant evaporating means normally located in the food compartment, mounting means for temporarily supporting the 55 refrigerant evaporating means upon the condenser, a refrigerant compressor, and flexible refrigerant conduit means connecting the condenser, compressor and evaporating means.

3. A refrigerator including a cabinet having a 60 food compartment therein provided with a door opening, a refrigerating system for cooling the food compartment including evaporating means in the food compartment and refrigerant liquefying means located outside of the food compartment and having compressor means mounted upon the cabinet below the food compartment, refrigerant conduit means extending from the evaporating means to the door opening, up from the door opening over the outer surface of the 65 cabinet across the outer portion of the top of the food compartment, and down the back of the cabinet to the compressor means, an ornamental front cover for the exposed portion of the refrigerant conduit means at the front of the cabinet, a 70 door for the door opening having a portion, when

the door is closed, which overlaps a portion of the ornamental cover, and an ornamental removable top cover for the cabinet which conceals the refrigerant conduit means extending across the top of the food compartment and which has a 5 flanged edge portion which overlaps a portion of the ornamental front cover.

4. A refrigerator including a cabinet having a food compartment therein provided with a door opening, a refrigerating system for cooling the food compartment including evaporating means in the food compartment and refrigerant liquefying means located outside of the food compartment and having compressor means mounted upon the cabinet below the food compartment, 10 said cabinet having an outwardly directed notch in the front upper part thereof, refrigerant conduit means extending from the evaporating means through the notch and over the top of the food compartment to the compressor means, ornamental means associated with the refrigerant conduit means for ornamenting the portion of the cabinet adjacent the refrigerant conduit means, and an ornamental top cover mounted upon the upper portion of the cabinet and concealing the 15 conduit means extending across the top of the food compartment.

5. Refrigerating apparatus including a cabinet having a food compartment therein surrounded by insulated walls, said food compartment having a door opening and a door therefor, an evaporating means within the food compartment, refrigerant liquefying means located outside the food compartment, refrigerant conduit means extending from the evaporating means out of the food compartment up over the portion of the outer surface of the cabinet above the door opening and across the top wall of the food compartment to the refrigerant liquefying means, and a movable top covering means extending over the 20 top wall of the food compartment concealing the 25 conduit means extending across the top wall of the food compartment.

6. Refrigerating apparatus including a cabinet having a food compartment therein surrounded by insulated walls and outer sheet metal walls, said food compartment having a door opening and a door therefor, an evaporating means within the food compartment, refrigerant liquefying means located outside the food compartment, 30 said outer sheet metal walls having an inwardly extending vertical depression therein forming a notch in the outer wall above the door opening, refrigerant conduit means extending from the evaporating means on the outer side of the sheet 35 metal walls through said notch to the refrigerant liquefying means, and covering means for concealing said notch and the refrigerant conduit means extending therethrough.

7. A packaging or shipping assembly including 40 a condenser in the form of an oblong flat rigid member having operative flexible pipe connections with a motor-compressor unit and an evaporator, said motor-compressor unit and evaporator being detachably secured to said condenser 45 and the flexible pipe connections being so bent as to make the whole into a compact form capable of being readily inserted into a packing case.

8. Refrigerating apparatus including a cabinet having a food compartment therein surrounded 70 by insulated walls and outer sheet metal walls, said food compartment having a door opening and a door therefor, and evaporating means within the food compartment, refrigerant liquefying means located outside of the food compartment- 75

ment, refrigerant conduit means extending from the evaporating means out through the door opening and over a portion of the outer sheet metal wall of the food compartment to the refrigerant liquefying means, and covering means for concealing a portion of the conduit means extending over the outer wall of the food compartment.

9. Refrigerating apparatus including a cabinet 10 having an insulated food compartment therein, a refrigerating system for cooling said food compartment including an evaporating means within the food compartment and a refrigerant liquefying means located outside the food compartment 15 having a portion at the rear of the cabinet, refrigerant conduit means extending from the evaporating means up over the front wall of the cabinet and rearwardly completely across the top of the cabinet to the liquefying means, an ornamental covering means extending over exposed 20 portions of the refrigerant conduit means for concealing the conduit means.

10. Refrigerant apparatus including a cabinet having an insulated food compartment therein, 25 a refrigerating system for cooling said food compartment including evaporating means within the food compartment and a refrigerant liquefying means located outside the food compartment and having a portion beneath the food compartment, refrigerant conduit means extending from the evaporating means up over the front wall of the cabinet thence rearwardly across the top 30 wall of the cabinet and down the back of the cabinet to the portion of the liquefying means beneath the food compartment, and covering means extending over the exposed portion of the refrigerant conduit means for concealing the conduit means.

11. A packaging or shipping assembly including a condenser in the form of a generally oblong 40 flat rigid member having operative flexible pipe connections with a motor-compressor unit and an evaporator, said evaporator being detachably secured to said condenser and the flexible pipe connections between the evaporator on one hand and the motor-compressor unit and the condenser on the other hand being bent so as to make the whole into a compact form capable of being readily inserted into a packing case.

12. A packaging or shipping assembly including 50 a condenser, a motor-compressor unit and an evaporator, said motor-compressor unit having operative flexible pipe connections with the condenser and the evaporator, said motor-compressor unit being detachably secured to said condenser and the flexible pipe connections connected to the motor-compressor unit being bent 55 so as to make the whole into a compact form capable of being readily inserted into a packing case.

60 13. A packaging or shipping assembly including a condenser, a motor-compressor unit and an evaporator, said evaporator having operative flexible pipe connections with the motor-compressor unit and the condenser, said evaporator being 65 detachably secured to said condenser and the

flexible pipe connections extending from the evaporator being bent so as to make the whole into a compact form capable of being readily inserted into a packing case.

14. Refrigerating apparatus including a cabinet 5 having a food compartment therein surrounded by insulated walls, said food compartment having a door opening and a door therefor, said cabinet having a finished metal exterior wall disposed over the insulated wall adjacent said door opening, a cooling element of a closed fluid 10 circulating system within said food compartment, means located outside of said food compartment for circulating a cooling fluid medium to and from said cooling element, said closed system 15 including conduit means extending between said cooling element and said circulating means and having a portion thereof lying over said finished metal exterior cabinet wall adjacent the door opening of said food compartment, and means 20 covering said portion of said conduit means and cooperating with said outer cabinet wall to form a part of the exterior finish of said cabinet.

15. Refrigerating apparatus including a cabinet 25 having a food compartment therein surrounded by insulated walls, said food compartment having a door opening and a door therefor, said cabinet having a finished metal exterior wall disposed over the insulated wall adjacent 30 said door opening, a cooling element of a closed fluid circulating system within said food compartment, means located outside of said food compartment for circulating a cooling fluid medium to and from said cooling element, said closed system 35 including conduit means extending between said cooling element and said circulating means and having a portion thereof lying over said finished metal exterior cabinet wall adjacent the door opening of said food compartment, and ornamental means covering said portion 40 of said conduit means and being removably secured to said outer cabinet wall to form a part of the exterior finish of said cabinet.

16. Refrigerating apparatus including a cabinet 45 having a food compartment therein surrounded by insulated walls, said food compartment having a door opening and a door therefor, said cabinet having a finished metal exterior wall disposed over the insulated wall adjacent said door opening, a cooling element of a closed fluid 50 circulating system within said food compartment, means located outside of said food compartment for circulating a cooling fluid medium to and from said cooling element, a depression formed 55 in the exterior cabinet wall adjacent said food compartment and above the door opening there- to, said closed system including conduit means extending between said cooling element and said circulating means and having a portion thereof disposed in said depression, and an ornamental 60 covering means for concealing said depression and the conduit portion disposed therein and co- operating with said outer cabinet wall to form a 65 part of the exterior finish thereof.

HARRY B. HULL.
